UNITED STATES PATENT OFFICE

2,305,235

ACCOUNTING DEVICE

Edward D. Byrnes, Chicago, Ill.

Application August 1, 1940, Serial No. 349,379

6 Claims. (Cl. 281—44)

The invention relates to an accounting device, and particularly to a device permitting the convenient accumulation of data from a plurality of record sheets.

Various apparatus have been introduced on the market, known as summary boards, where the record sheets are placed alongside of one another in overlapping relation, whereby desired data may be ascertained. But these apparatus are cumbersome and inconvenient, nor do they permit rapid calculations.

It, therefore, constitutes an object of the invention to provide a device wherein a plurality of record sheets are arranged so that only such portions of the record charts which are correlated for summarizing certain data are exposed to view.

A further object is the provision of means for simultaneously indexing all of the record sheets so that selective correlated portions are exposed to view for summarizing their data.

It is a further object to provide means for automatically restoring the record sheets to initial position when no further summarizing is desired.

Another object constitutes the provision for an audible signal when the indexing of the record sheets has been completed.

A still further object is to provide a marker to designate a particular place on the record sheets to facilitate reverting thereto after an interruption.

It is also an object to provide certain features of construction and arrangement of parts tending to enhance the utility and efficiency of a device used for the accounting system.

With these and other important objects in view, which will become apparent from a perusal of the invention, the latter comprises the novel steps of an accounting system and the means for carrying out the same, as described in the following specification, particularly pointed out in the claims and illustrated in the accompanying drawings, in which:

Fig. 1 is an end view of a device constructed in accordance with my invention.

Fig. 2 is a top plan view of the device.

Fig. 3 is a section on the line 3—3 of Fig. 1.

Fig. 4 is a section on the line 4—4 of Fig. 2.

Fig. 5 is a fragmentary section, on line 5—5 of Fig. 4.

Fig. 6 is a section on the line 6—6 of Fig. 3.

Fig. 7 is a section on the line 7—7 of Fig. 3.

Fig. 8 is a fragmentary perspective view of a record sheet.

Figs. 9 and 10 show, respectively, a part of the holding device for the record sheet.

Referring to the several views in the drawings, 10 designates a base plate to which is secured a housing 11 of rectangular cross section comprising side walls 12 and 13, end walls 14 and 15, and a top wall 16.

A plurality of casings 17, 18, 19, 20 and 21 are arranged in said housing. The casings are in spaced relation from each other and extend from the base plate 10 to a plane short of the top plate 16. A partition 22 is provided near the right side (as viewed in Fig. 4) of each casing to provide a narrow channel for a purpose hereinafter further referred to.

A rectangular bar 23, constituting a frame, encompasses the casings and is connected by pins 24 to endless chains 25 and 26, respectively trained around sprocket wheels 27 and 28. The sprocket wheel 27 is journaled on a stud 29 extending from the housing walls 14 and 15, and the sprocket wheel 28 is fast on a shaft 30, journaled at one end in the housing wall 14, whereas the other end is journaled in the outer wall 31 of a gear chamber 32.

The casing 21 has a cut away portion 33 to clear the shaft 30 and, likewise, the housing wall 15 is cut away as at 34, which is closed by the wall 31 which is provided with a flange 35.

30 A plurality of record sheet holders, generally designated by 36, are secured to the frame 23. Each holder comprises two bars 37 and 38 (Figs. 5, 9 and 10) which are hingedly connected to clampingly hold the edge of a record sheet, as will be hereinafter further explained.

35 The bar 38 has four spaced hinge sleeves 39 between which sleeves 40 of the bar 37 fit in registry. A rod 41 extends through the aligning sleeves and, at its ends, an abutment member 42 40 is secured to prevent longitudinal movement of the rod.

A coil spring 43 surrounds the middle portion of the rod 41, having one end secured to the rod and the other end bearing against the bar 37 so as to force the bars into clamping relation.

The bar 38 is provided with a plurality of rectangular lugs 44, a pair of triangular lugs 45, and a pair of pins 46. The bar 37 has cut away portions 47 to clear the lugs 44 and triangular openings 48 in which the triangular lugs 45 are received. Likewise, holes 49 in the bar 37 receive the pins 46.

50 The record sheet 50 similarly has cut away portions 51 to clear the lugs 44, triangular cut

out portions 52 to clear the lugs 45, and slots 53 to permit the record sheet to clear the pins 46.

It is evident that when a record sheet 50 is inserted in the holder, which may be opened by a handle 54 on the bar 31, that the record sheet is accurately aligned by the lugs and pins previously mentioned, and when the handle is released to permit the holder to close under the influence of the coil spring, that the record sheet is securely gripped and held in proper registry with the other sheets of the device. The free end of each record sheet is threaded into the interspace between the casing and the appertaining partition 22 (Fig. 4).

The top wall 16 is formed with longitudinal openings 55 (Fig. 2) so that only one column of each record sheet is open to view, whereas the remaining part of the record sheets are obstructed from view.

It is clear, therefore, that if the frame 23 is actuated by an indexing movement downwardly from the top position, shown in Fig. 4, that successively the remaining columns of each record sheet will be brought into view, whereby data from correlated columns of the record sheets may be conveniently gathered.

The mechanism for imparting indexing movement to the frame 23, and thereby to the record sheets 50, will now be described.

As shown in Fig. 3, the drive shaft 30 has secured thereto a pinion 56 in mesh with a gear 57 fast on the inner end of a stud shaft 58 journaled in a bearing 59 integral with the wall 31 of the gear chamber.

Adjacent to the gear 57 is a gear 60 which is engaged by a pawl 61 (Fig. 6), pivotally secured on a pin 62 projecting from the wall 31. A spring 63 urges the pawl into engagement with the gear 60 to permit rotation of the gear in clockwise direction, as viewed in Fig. 6, but preventing opposite rotation.

The pawl is provided with a pin 64 extending through an arcuate slot 65 in the wall 31 and provided with a knob 66. Upon pushing the knob towards the left, as viewed in Fig. 6, the pawl is released from engagement with the gear 60, permitting rotation of the gear 60 and consequently shaft 30 in either direction.

The shaft 58 is provided with a knob 67 to facilitate rotation of the stud shaft 58 whereby drive is imparted to the shaft 30.

A clock spring 68 has one end secured to the stud shaft 58 and the other end is secured to an arm 69 projecting from the wall 31. A disk 70 is fast on the stud shaft 58 and is provided with a number of peripheral indentations 71 corresponding to the number of columns provided on each record sheet.

A tubular casing 72 is secured to the wall 31. The casing is closed at the top and open at the bottom to permit the ejection of a pin 73 under the influence of a spring 74 to cause engagement of the spring with the periphery of the disk 70.

It is evident that upon rotation of the knob 67, and the indexing of the sheets, a click will be heard by the snapping of the pin into the disk indentation 71, thereby informing the operator to abandon further rotation of the knob, thus giving an audible signal that proper indexing has been completed and the desired column of the record sheets has been brought into visual position.

On top of the wall 16 is provided rod 75 extending longitudinally of the housing at the left side thereof, as viewed in Fig. 2, and supported in lugs 76 upstanding therefrom.

A runner 77 is slidably mounted thereon and has a chamber in which a ball 78 is forced into engagement with the rod 75 by a spring 79.

5 A rod or beam 80, constituting a line finder, is secured to the runner and carries a runner 81 which is equipped with an index 82 so that when the calculations are being interrupted the index may be placed opposite the last data noted and the operator may easily establish the next data to be calculated when resuming work. The top wall 16 is secured by a hinge 83 to the housing 11 and thus may be lifted.

The operation of the device is as follows:

When a plurality of record sheets are to be placed in the accounting device, the top wall 16 is lifted up, affording access to the frame 23 and, upon opening the sheet holders 36, the sheet is inserted in such holders with the free ends of the sheets being inserted between the interspace of each casing and the appertaining partition 22, as will be readily understood by reference to Fig. 4.

Thereupon, the top wall 16 is closed and the line finder 80 is moved into position where the appertaining data may be easily read off.

20 The data of each column of each record sheet visible through the openings 55, having been tabulated, the adjoining column of each sheet must be brought into view through the openings 55.

25 To this end, the knob 67 is turned ratcheting over the pawl 61 and as soon as the next column is in position and exposed to view, the pin 73 enters an indentation 71 of the disk 70, affording a click and apprising the operator that the proper position has been reached.

30 This procedure is continued until all of the columns have been successively brought into proper position to be viewed through the openings 55, and each time a new column is tabulated, the audible signal is rendered to indicate proper position.

35 The successive turning of the knob 67 tensions the clock spring 68 since the pawl 61 prevents a return movement of the gear 60, so that when 40 the last column has been reached, the spring 68 is fully tensioned, and upon release of the pawl by actuation of the knob 66, the spring 68 is unwound and a quick motion is imparted to the drive shaft 30 and the chains 25 and 26, causing 45 rapid ascension of the frame 23 and, consequently, the return of the record sheets to the original position, as indicated in Fig. 4, where they may be easily removed from the holders and a new set of record sheets may be introduced.

50 55 While the drawings show a preferred embodiment of the invention, numerous changes and alterations may be made without departing from the spirit of the invention.

I claim:

60 65 1. A device of the character described, including a housing having a plurality of openings at the top, a plurality of spaced casings in said housing defining channels therebetween, a rectangular frame encompassing said casings, holders on said frame holding record sheets with desired portions underneath said openings and with the remainder of the sheets arranged in said channels, and means for widening said frame to successively expose different portions of said record sheets through said housing openings.

70 75 2. A device of the character described, including a housing having a plurality of openings at the top, a plurality of guide channels in said housing, a frame encompassing said channels, holders on said frame for record sheets with por-

tions underneath said openings, and the remainder depending in said channels, and means for reciprocating said frame.

3. A device of the character described, including a housing having a plurality of openings at the top, a plurality of guide channels in said housing, a frame encompassing said channels, holders on said frame for record sheets with portions underneath said openings, and the remainder depending in said channels, means for moving said frame downwardly step by step, and means for causing a quick ascent of said frame.

4. A device of the character described, including a housing having a plurality of openings at the top, a plurality of guide channels in said housing, a frame around said channels, means on said frame for holding record sheets with portions underneath said openings and the remainder depending in said channels, means for causing said frame to descend step by step, and an automatic signal indicating the completion of each step.

5. A device of the character described, including a housing having a plurality of openings at the top, a plurality of guide channels in said housing, a frame around said channels, holders on said frame for record sheets, each holder comprising a pair of bars hingedly connected at one edge and urged in closed position, the record sheets being held to expose portions through said openings and depending in said channels, and means for causing said frame to descend step by step and to ascend rapidly.

6. A device of the character described, including a housing having a plurality of openings at the top, a plurality of guide channels in said housing, a frame around said channels, means on said frame for holding record sheets with portions underneath said openings and the remainder depending in said channels, means for causing said frame to descend step by step and to ascend rapidly, and an automatic signal indicating the completion of each step.

EDWARD D. BYRNES.
